UNITED STATES PATENT OFFICE.

HENRY R. WAHL, OF CHICAGO, ILLINOIS.

HYDRAULIC SEPARATOR.

Original application filed November 6, 1915, Serial No. 60,019. Patent No. 1,306,361, dated June 10, 1919.
 Divided and this application filed June 6, 1919. Serial No. 302,156.

To all whom it may concern:

Be it known that I, HENRY R. WAHL, a citizen of the United States, and a resident of Chicago, in the county of Cook and State 5 of Illinois, have invented certain new and useful Improvements in Hydraulic Separators, of which the following is a full, clear, and exact specification.

This invention relates to improvements in 10 hydraulic separators for crushed ores and is a division of my co-pending application filed November 6, 1915, Serial No. 60,019.

My invention relates to improvements in 15 "sand-slime classifiers" particularly those known as mechanical classifiers wherein heretofore the sand, together with some of the slimes, settles on the inclined bottom of a containing tank, from which they are discharged at a point higher than the water 20 level by a mechanical means, such for example as reciprocating scrapers, or helical conveyors, the agitation of which is intended to prevent to a certain extent the settling of the slimes, and promote disintegration of the 25 sand enclosing slimes, further augmented if desired by water sprays directed against the sand before being discharged; which operation, however, necessitates repetitions detrimental to efficiency and capacity.

30 My invention further relates to improvements in "dewatering machines" for crushed ore, or tailings, heretofore discharged from their containing tank by a scraping operation, such as an endless chain with scraper 35 flights, or a revolving wheel with attached scrapers, the use of which is objectionable because of the wear and tear thereto from their frictional contact with the bottom of the tank, and which for the discharging of 40 crushed ore is more seriously objectionable because of pulverizing the ore and thereby producing slimes, which are difficult of recovery by mechanical means of concentration.

45 For a clearer understanding of my present invention, its objects, and the importance of the results attributable and thereby secured, it is to be observed, that in the preliminary preparation of ore for treatment by suitable processes for the recovery of the valuable mineral therein, it is first crushed by machines to a predetermined degree of fineness in order to liberate the mineral particles from the enclosing gangue rock.

55 For the operation of crushing the ore, the

well-known "ball or tube mills" have merited most consideration, and the product from these machines consists of particles ranging in size from a very fine powder, usually termed slimes, and increasing to sizes distinguished as fine and coarse sand. 60

In ore milling it is usually necessary for practical and economical reasons to grade the ore after crushing into two or more convenient groups of sizes before treatment on 65 machines adapted thereto or when necessary, only the finer group, or "slimes" is selected as the desired product, and the coarser sands are returned to the crusher for further reduction. This is accomplished by the various well-known types of mechanical and hydraulic sand-slime classifiers, to which this 70 invention relates.

In my co-pending application filed November 6, 1915, Serial No. 60,019, I have described and claimed, among other things, means by which it is possible and practical to separate the slimes from ores, classify the sands therein by a hydraulic current and discharge them from the machine, and also dehydrate the coarsest particles or "gravel" 75 and discharge them in a dehydrated condition, as a separate group from the machine, continuously, and therefrom by a single operation. 80

The invention of my present application is, however, directed to a means for the separation of the slimes from the coarser sands and particles of crushed ore and the dehydration of the separated coarser sands 90 by a single continuous operation, and by substantially the same means before described in my co-pending application, the claims for which are confined to the separation of the slimes from the sands and coarser particles, 95 before the classification of the sands and the subsequent dehydration and discharge of the coarser particles from the machine.

The prime object of my present invention, broadly stated, is to provide a hydraulic 100 separator for crushed ores, wherein the slimes are separated from the ores by rising currents of water, with means for concurrently therewith dehydrating the ores before their discharge therefrom. 105

Another object of my invention is to provide a hydraulic separator with means mechanically agitating crushed ores containing slimes constantly ascending to the surface of a rising current of water in a contain- 110

ing tank, from which the slimes continuously discharge, and whereby a complete separation of the slimes from the ore particles is made possible and practical.

5 A further object of my invention is to provide a hydraulic separator and classifier with means for mechanically agitating ore pulp in currents of water at a point between the rising separated slimes and the 10 separating point therefrom of the sands, whereby the slimes are prevented from settling with the sands.

More specifically stated, the object of my present invention is to provide the hydraulic 15 separator and classifier of my original application with means whereby the line of division between any group of particles consisting of slimes or finer sands and those consisting of coarser sand, may be variably 20 and definitely controlled after their passage from the containing tank in which they were roughly separated.

With these ends in view, my invention finds embodiment in certain features of novelty 25 in the construction, combination and arrangement of parts by which the said objects are attained, all as hereinafter fully described with reference to the accompanying drawings, and more particularly pointed out in the claims.

In said drawings:—

Fig. 1 illustrates an elevation in vertical section on the line 1—1 of Fig. 2.

Fig. 2 is a vertical section taken on the 35 line 2—2 of Fig. 1.

Fig. 3 is a vertical section taken on the line 3—3 of Fig. 2.

Fig. 4 is a transverse detail of the water supply pipes taken on the line 4—4 of Fig. 2.

40 Fig. 5 is a detailed vertical section taken on the line 5—5 of Fig. 2.

Fig. 6 is an enlarged detail side elevation showing the hopper receiving the dehydrated ore discharged from the buckets 45 and the chute through which such ore is discharged from the machine.

Fig. 7 is a vertical section through a modified construction of a hydraulic separator and classifier on the line 7—7 of Fig. 8, with 50 a portion of the link belt chain broken away.

Fig. 8 is a vertical section on the line 8—8 of Fig. 7.

Fig. 9 is a vertical section on the line 55 9—9 of Fig. 8.

Fig. 10 is a partial plan of Fig. 9.

Fig. 11 is a cross section on the line 11—11 of Fig. 8.

Fig. 12 is a plan of Fig. 11.

60 Fig. 13 is an elevation in section of Fig. 11.

Similar characters of reference indicate the same parts in the several figures of the drawings.

65 In the following description reference let-

ters A, C, E, F, L, M, N, O and P designate the same elements of the machine illustrated by Figs. 1 to 35 inclusive of the drawings accompanying my original application and are fully described therein. For clearness 70 of description, however, and understanding of the purposes of the structure in which my invention finds embodiment, the functions of the elements mentioned above will again be pointed out.

With reference to Figures 1, 2, 7 and 8, the machine may be generally described as consisting of an operating water tank A, preferably filled with clear water supplied from any exterior source and admitted to 80 the tank through the water supply system C.

Detachably secured to and submerged in the contents of the water tank A is a slime separating hopper E, supplied with crushed ore from a feed box F. Encircling the hopper E and partially submerged in the tank A is the rotor L, consisting of a short cylinder with closed periphery and relatively large end openings, forming a U-shaped section thereof, the projecting end plates of which terminate in tires I, which rest and roll upon two pairs of flanged rollers 2, suitably mounted on shafts 3, projecting through the sides of the tank A, and caused to revolve thereon, by power transmitted by a link chain belt 4, to a circular rack 5, concentric with the periphery of the rotor, of which all details are more fully described in my original application.

The shafts 3 are supported and guided in journal boxes (not shown) enclosed by the water-tight casings 6, secured to the tank, the lower portions of which terminate in a base 7, resting upon the foundations 100 8.

Pivoted between the end plates of the cylinder and movably secured thereto, are a series of scoop shaped buckets or dehydrating ore dischargers M, spaced at intervals near the wall of the periphery, the purpose 105 of same being to elevate out of the water, dehydrate and finally to overturn about their pivots 9 by gravity, or if need be, by a positive mechanical means and discharge the contents deposited therein after its passage through the slime separating hopper E, through a forcible impact against the next preceding bucket, down into the discharge hopper N, Figures 1, 2, 6, 7 and 8, whereafter the ore passes through a spout in same and 110 may be carried off by the usual means for subsequent treatment.

In order to steady the rotor while revolving and maintain its vertical position on the rollers, two pairs of guide rollers 10, Figs. 1 and 7, are provided above the water in tank A, at diametrically opposite points of the tires and bearing against the sides of same, in opposition to each other.

The driving mechanism O, Figs. 1, 7 and 130

8, consists of a rigid frame 11, supporting the bearings for the shafts 12 and 13, pulleys 14, and reduction gearing 15, power to which may be transmitted by belt or any usual means and thereby operating a relatively small sprocket chain wheel 16, in alignment with the circular rack surrounding the periphery of the rotor L and imparting motion to same by an endless link chain belt 4, 10 in mesh therewith.

Eccentric jacks P, Figs. 1 and 2 (not shown in Figs. 7 and 8) consisting of shafts 18, located at suitable places below the rotor, project through the sides of the water tank A, with stuffing boxes 19 for same secured thereto, and rigidly mounting two pairs of eccentrics 20, grooved for and provided with straps 17 opposite the tires on the rotor, by means of which straps a lifting force can be exerted against same when the shafts are turned by a lever and the rotor held in position, when it becomes necessary to remove the supporting rollers for repairs through suitable doors provided in the ends 25 of tank A, opposite the rollers and closed water-tight by covers 21.

Detachably secured to the opposing side walls of tank A, are stationary deflecting plates 22, converging inwardly and overlapping in close proximity the circular flanges 23, riveted to each side plate of the rotor. The clearance space between flanges 23 and deflecting plates 22 is the only means of passage for the clear water surrounding the outside of the rotor in to the interior space occupied by the slime separating hopper E, the direction of current varying from horizontal at the surface to an angle of 45 degrees downward at the bottom, according 40 to the particular point considered with reference to a level line.

The water supply system C consists of a header pipe 24, with a valve 25, see Fig. 4, provided with suitable flanges and connections for the branch pipes 26, which terminate in cocks 27, and from crosses 28 located at suitable points on the branch pipes 26, short nipples and flanges form a vertical connection of the branch pipes with the bottom of tank A.

The contracted end portion of pipe 24 (not shown in Fig. 8) is continued to the opposite side of tank A, and terminates at a point 24^a, a short distance up from the bottom and in open communication with same, thereby insuring a water supply should the other inlets 28 become choked, the water inlets 28, when necessary, serving also as drain outlets for ore dropped through the holes 29, 50 see Figs. 1, 6 and 7, provided in the periphery of the rotor L to the bottom of water tank A, and thereafter discharged from the tank by opening cocks 27.

The holes 29 in the periphery of the rotor

are respectively closed by valves 30, secured to the circular rack 5, in sockets 5^a, or, as in a modified construction (see Fig. 7) by the flat bent straps 5^b, and provide outlets for material at intervals of the periphery of the rotor in case the space below the slime separating hopper E becomes choked with same. The valves may be unseated by reversing the direction of rotation of the circular rack when the rotor is stationary, until the material below the hopper is discharged and upon again applying power to the driving pulley, the rack will move forward and thus reset the valves.

With reference now to Figs. 1 and 2, the slime separating hopper E, consists of opposing downwardly converging side walls 31, extending across, secured to and closed at their ends by the side walls of the operating tank, and extending from the upper edge of the tank downwardly to a point shortly above the inner edges of the side flanges of the rotor.

The converging sides of the slime separating hopper, together with deflecting plates 32, secured to the side walls of the water tank serve to contract the bottom opening 33 of the slime separating hopper for directing the crushed ore therefrom to the rotor, for their elevation and dehydration by means of the buckets M before described for that purpose, and the discharge of the ores into the discharge hopper N, as before mentioned.

In operation the crushed ore is introduced to a hopper 34, provided with a perforated bottom 35, submerged in the contents of the water tank and through which the ore discharges into the slime separating hopper, with the result that the coarser particles descend therethrough, and are conducted as before stated into the rotor in the path of the dehydrating buckets, and from which the slimes are carried upwardly by the rising currents of water, and discharged through openings 36 therein into supplemental slime separating chambers 37 at opposite sides of the slime separating hopper E.

It will now be observed that the velocity of the ascending currents of water in the slime separating hopper is substantially greater than that of the water in the supplemental slime separating chambers 37, and from which the slime containing water overflows into troughs 38, one for each supplemental slime-separating chamber, and from which the slimes are conducted through pipes 39 for subsequent treatment, and that as a result of this difference in velocity, coarser particles of sand will be precipitated from the slimes discharging into the supplemental slime separating chambers 37 depositing on the bottom thereof, and from which it is desirable to remove and dehy-

drate with the still coarser particles discharging through the bottom of the slime separating hopper E.

As a convenient and effective means for this discharge of the sands from the supplemental slime-separating chambers, there is preferably employed a shaft 40 journaled at its opposite ends in suitable stuffing boxes 41 in the outer end walls of the water containing tank, to which shaft are secured screw conveyors 42, one for each supplemental chamber, the inner ends of which project through and beyond the opposing walls of the slime-separating hopper E, which inner ends are enclosed by a pipe 43, through which the deposited sands are conducted and thence directed to the elevating dehydrating buckets by means of spouts 44, which may be formed integral with the pipe.

Each pipe 43 at its opposing ends is provided with openings through which are projected adjustable stuffing boxes 45 and a gland 46, the opposite ends of the pipe being fixed to the side walls of the water tank.

Sleeved on the shaft 40, and rigidly secured to the pipe 43, is a follower 47, one end of which projects into the stuffing box and the other into a casing 48, forming an oil chamber to which oil is supplied from a cup 49, connected by a pipe 50 with the oil chamber 48 and supported by such pipe in a plane above the level of the water in the tank.

The follower 47 performs three functions, that of an oil tight closure for the oil chamber 48, a bearing for shaft 40, and at the same time a gland for adjustably compressing and tightening a suitable packing contained in a chamber 51 in the stuffing box 45, and for which purpose the follower is provided with a flange 52 for the reception of one or more adjusting screw bolts 53 passing therethrough into the bar 46 supporting the stuffing box, and therefore a means of drawing same against the follower 45 to compress the packing. See Figs. 1, 6, 7, 8 and also Fig. 13 showing an enlarged view of same.

For operating the shaft and the screw conveyors thereon, one end of the shaft is provided with a pulley 54 for a belt 55, passing around a pulley 56 on a shaft 57, connected by a belt 58 around pulleys 59 and 59^a, on a shaft 60, supported by and having its bearing in brackets 61 secured to a frame (see Fig. 1) supported on the water tank on which shaft is a pulley 62 driven by any suitable means from any source adapted therefor.

As a convenient means for conducting the dehydrated coarser sands from the hopper N to some suitable place for subsequent treatment, the hopper (see Fig. 6) is provided with a spout 63, discharging upon a belt conveyor, the bottom side 64 of which is

supported upon rollers 65, upon a shaft 66, 65 journaled at its ends in suitable brackets 67.

The top side 68 of this belt is supported at intervals of its length upon horizontally arranged rollers 69, between which and at the opposite edges of the belt are converging rollers 70, suspended from suitable supports (not shown) sustaining the adjacent sides of the belt in an upwardly inclined position, and thereby converting the top side of the belt into a traveling trough for conducting the dehydrated ore away from the separating machine, but for which purpose any other suitable form or construction of conveyor may be used.

In operation for the separation of slimes 80 from coarser sands subsequently dehydrated, the tank is first filled with water as before described, from any source suitable therefor, to a level with the overflow of the water therefrom into the trough 38, followed by 85 the introduction of water to the bottom of the tank from the pipe system C before described, and in turn followed by the discharge of ore from the feed hopper 34 through the perforations in the bottom 90 thereof, downward by gravity into the slime separating hopper E.

Following the entrance of the ore into the slime separating hopper, the rising current of water meeting the slimes descending 95 in the hopper are thereby prevented from settling in the slime hopper, but are lifted and pass out through the opposing end openings 36 in the side of the hopper, which pass thence into the supplemental slime-separating chambers 37, whereafter in their passage toward the overflow the heavier particles thereof settle to the bottom, and are conducted thence by the screw conveyor to and through the contracted end of the slime-separating hopper, whence they descend by 100 gravity to a position of rest upon the opposing surface of the water, dehydrated and discharged from the hopper N as before described.

With the rising of the slimes, and their discharge into the trough 38, and thence through the pipe 39, the finer sands are discharged from the machine with the slimes, it being the purpose and intention in the 115 structure described to separate and dehydrate only the coarser sands contained in crushed ore, and whereby the slimes discharged from the machine contain a minimum of fine sand.

It is now to be observed that in the construction shown by Figures 2 and 3, the weir or edge over which the slimes pass into the troughs 38, after their passage through the supplemental slime-separating chambers, is 125 in a fixed position and invariable in distance from the openings 36 in the slime separating hopper E, in consequence of which, the

slimes passing through the openings, together with the coarser sands, it is not desired to discharge with same, are caused to settle below the level of the overflow and subsequently are returned by the screw conveyors to the rotor and dehydrated.

In ore milling practice, however, for practical and economical reasons, it is frequently found desirable to treat the slimes from crushed ore and coarser sands together, and return only such particles as have not yet been sufficiently crushed to the crushing machine for further reduction.

My invention therefore includes a means whereby it is possible to separate from and discharge with the overflowing slimes, such coarser sands as may be desired therewith and dehydrate only the coarsest sands which require further crushing, by the same general arrangement of elements as already described in the machine, but with such modifications now to be described in the following and more specifically pointed out in the claims.

With reference now to Figures 7 and 8, reference characters A designate an operating water tank, C is the water supply system, E is the slime-separating hopper, F is the feed hopper, L is the rotor, M are the pivoted dehydrating ore dischargers, N is the discharge hopper, and O is the driving mechanism, all of substantially the same construction as previously described.

For the particular object in view, I prefer to employ a slime separating hopper with its four side walls converging downwardly and terminating in a short contracted bottom opening 71, in alignment with the vertical axis of the rotor. Adjustably secured and conforming in shape with the side walls of the hopper is a baffle plate 72, between which and the adjacent wall of the hopper, the slimes pass upwardly and are discharged through an elongated opening 73 therein, into a supplemental slime-separating chamber 74.

In Figures 7 and 8 I have shown a preferred construction having but a single supplemental slime-separating chamber in connection with the slime hopper E, but it is to be understood that two supplemental chambers, as shown in Figs. 1 and 2, can be employed if so desired.

In order to promote the disintegration of the descending ore within the hopper E and prevent the settling of coarse particles which it is desirable to discharge with the slimes, I employ a V-shaped perforated agitating plunger 75, suspended within and free from the contracted portion of the hopper by the rod 76 attached thereto and at its upper end to an eccentric 77, which may be of any usual construction for such purpose.

The eccentric is actuated by a short shaft

78, supported by bearings (not shown) at each end 79, rigidly secured to a frame 80, which is supported by the side walls of the tank A. The collars 81 restrain the end movement of the shaft and at one end is a pulley 82, driven by a belt 83, from the pulley 84 located on the shaft of the driving mechanism O.

The agitating plunger 75 receives a vertical reciprocating motion when the shaft 78 is revolved and is guided laterally by a bar 85, secured to the side walls of the hopper. In operation the crushed ore is introduced to a hopper 86 (see Fig. 8), provided with a perforated bottom 87, through which the ores descend into the slime-separating hopper, until they reach the zone of agitation directly above the plunger, with the result that a separation of the ore particles takes place, during which separation the coarsest particles immediately sink and pass through the perforations in the plunger and are conducted into the rotor in the path of the dehydrating buckets and thereby elevated and discharged from the machine, while the lighter particles, kept in suspension by the agitation, pass upward in the narrow space between the baffle-plate 72 and the side wall of the hopper and thence outward in a horizontal direction through the opening 73 and into the supplemental chamber 74, at the surface of the water therein.

The water level in the supplemental chamber and the hopper E, is indicated by the line 88, and is so maintained by a movable overflow tray 89, consisting of a narrow and shallow pan shaped structure with its bottom sloping from each end toward the center (see Figs. 9 and 10), and having a seat 90, conforming to and making a close, watertight contact with the discharge pipe 91, 100 upon which it rests.

The two side edges 92 of the tray form a weir over which the slimes overflow, and are maintained in a level position by the adjusting screws 93, in lugs attached to the tray and bearing against the side walls of the supplemental chamber. An elongated outlet 94 for the slimes is provided in the bottom of the tray, coinciding with equal sized openings 95, in the upper side of the discharge pipe 91, of which there are a number of openings spaced a short distance apart over the full length of the pipe, and closed to watertightness by the removable plugs 96; the purpose of these plugs being 110 to close all openings in the pipe with the exception of one, which is in communication with the opening in the tray, and also to permit the tray to be moved at will over any of the openings by shifting the tray with reference to the plugs, and in so doing the distance between the openings 73 in the hopper E, and the overflow edges of the tray is either

lengthened or shortened to accord with the size of sand particles which it is desirable to discharge with the slimes.

The pipe 91 is closed at the end nearest 5 the tank A, to which it is secured by a U-shaped strap 97, the other end being open and provides an outlet through the end wall of the supplemental chamber by means of the pipe flanges 98, secured together by bolts 10 99 and terminating in a T 100, from which the discharged slimes may be conducted away from the machine.

It is now to be observed that the slimes and coarser particles discharged from the 15 hopper E, through the opening 73, must traverse a distance within the supplemental chamber, directly dependent upon the position of the overflow tray on the pipe 91, and as a result of which, more or less 20 time is required for their passage.

As a further result, the coarser particles settle out of the current and only the lighter particles, it may be desirable to include with the slimes, pass over the edges of the overflow tray and are discharged from the 25 machine through the pipe 91.

Furthermore, the openings in the pipe 91 are so arranged that when the tray 89 is placed to coincide with the opening nearest 30 the hopper E, the distance between the tray and the outlet 73 is practically nothing, and under this condition the supplemental chamber 74 is not in use, and much coarser particles are discharged with the slimes than 35 when the tray is placed at any one of the other openings; which action is further augmented by the amount of agitation produced in the hopper E.

It is obvious that the rising currents in 40 the supplemental chamber 74, are of much less velocity than in the hopper E, and that as a result of this difference in velocity, coarser particles of sand will be precipitated from the slimes discharging into the supplemental chamber and settling to the bottom thereof, than in the space immediately 45 above the agitating plunger in the hopper, and which it is desirable to dehydrate and return to a crushing machine for further 50 reduction.

As a convenient and effective means for the removal of the coarser particles which have settled out of the current to the bottom of the supplemental chamber, there is 55 preferably employed a shaft 101, journaled at its opposite ends in a bearing combined with a stuffing box 102 upon which shaft is secured a screw conveyor 103.

The bearing and stuffing box (see Fig. 60 13) consists of a flanged bushing 104, secured to the end wall of the tank by rivets (not shown), and through the opening in the bushing is projected a gland 105, provided with a chamber 106, in which suitable 65 packing 107 is placed to encircle the shaft

101. Seated against the bushing 104, is a flanged bearing 108, recessed to provide a place for the gland, and having bolts 109, which serve as a means for drawing back the gland and for compressing the packing in 70 the chamber 106.

The bearing 108 located in the end wall of the supplemental chamber 74, is enclosed at one end, in order to take the end thrust of the screw conveyor, by means of the thrust buttons 110 interposed between the end of the shaft and the end wall of the bearing and are adjusted laterally by the screw bolt 75 111.

The shaft 101 projects beyond the bearing 80 located in the side wall of the water tank A, and mounted thereon is a driving pulley 112, for a belt 113, passing around a pulley 114, on a shaft 12, comprising a part of the driving mechanism O, previously described. The inner end of the screw conveyor 101, is enclosed by a pipe 115, provided with a discharge opening and spout 116, which projects a short distance into the hopper E, and through which opening the deposited coarser 85 sands are conducted into the zone of agitation above the plunger 75, and thereafter they descend into the path of the dehydrating buckets within the rotor L.

At the points where the shaft projects 90 through the side walls of the hopper E, are suitable thimbles 117 for deflecting the descending ore away from the shaft, and preventing the escape of the ore from the 95 hopper.

In operation for the separation of slimes and finer particles of sand from coarser particles subsequently dehydrated and returned for further crushing, the tank A and supplemental chamber 74 are first filled with water 100 from any source suitable therefor, to a level with the overflow of the water therefrom into the tray 89, followed by the introduction of water to the bottom of the tank from the pipe system C, before described, and in turn followed by the discharge of ore from the feed hopper F, through the perforations in the bottom thereof, downward by gravity 105 into the slime separating hopper E.

The rotor and agitating plunger having 110 been previously set in motion, the descending ore passes into the zone of agitation above the plunger, the rapid reciprocating motion of which prevents the settling of the slimes and finer particles and they 115 pass upward with the more rapid rising current in the passage formed between the baffle plate 72 and the adjacent wall of the hopper, and are discharged through the opening 73 into the supplemental slime-separating chamber 74. The coarser particles 120 not prevented from settling by the agitation pass downward through the perforations in the plunger and come to a state of rest on the periphery of the rotor, whereby they 125 130

are subsequently elevated and dehydrated by the buckets and discharged into the hopper N, and conducted away.

The slimes and finer particles having entered the supplemental chamber 74 at the level of the water therein, now flow with increased velocity across the full width of the chamber in a current of slight depth toward the overflow edges of the tray 89, but as 10 solids of greater specific gravity than water tend constantly to sink, the heavier particles included in the current tend to settle out directly proportionate to the distance between the tray 89 and the opening 73, and 15 are deposited on the bottom of the supplemental chamber, while the lighter particles and slimes reach the overflow edges of the tray and are discharged from the machine through the pipe 91. The coarser particles deposited on the bottom of the supplemental chamber are then removed by the screw conveyor in a more or less cohesive mass and returned to the agitation zone 20 above the plunger 75, where they are again disintegrated before passing downward 25 through the perforations in the plunger and thence also into the path of the dehydrating buckets and discharged from the machine.

30 Shifting the overflow tray 89 toward the hopper E, and increasing the stroke of the plunger 75, or if desired in addition, an increased rising current in the hopper by admitting more water through the pipe system, C, will result in the discharge of coarser particles with the slimes, and when the conditions are reversed, slimes only will be 35 discharged through the pipe 91; each element of the machine being separatively adjustable and therefore capable of being closely regulated.

While I have illustrated and described the preferred form of construction for carrying my invention into effect, this is capable of 45 variation and modification without departing from the spirit of the invention. I therefore do not wish to be limited to the precise details of construction set forth, but desire to avail myself of such variations and modifications as come within the scope of the appended claims.

Having thus described my invention, what I claim and desire to secure by Letters Patent is:

55 1. A hydraulic separator comprising in combination a water tank, a primary slime separating chamber, a supplemental slime separating chamber adjacent thereto, means for producing rising currents of water in 60 said chambers, discharging therefrom in substantially the same plane and mechanical means for conducting the finer sands depositing in the supplemental chamber in the path of movement of the coarser sands

separated from the slimes in the primary 65 chamber.

2. A hydraulic separator comprising in combination a primary slime separating chamber, a supplemental slime separating chamber directly receiving the overflow of 70 said primary chamber, means for producing constantly rising currents of water in said chambers, and conveyor means for conducting the sands deposited in the supplemental chamber into the primary chamber in 75 the path of the coarser sands descending through the latter.

3. A hydraulic separator comprising in combination a water tank, a primary slime separating chamber, a supplemental slime 80 separating chamber directly receiving the slimes discharging from the primary chamber, a connecting open passage-way towards the bottom of said chambers, means for producing in said chambers constantly rising 85 currents of water, and a conveyor projecting through said passageway adapted to conduct the deposited sands in the supplemental chamber into the primary chamber in the vicinity of the open bottom end 90 thereof.

4. A hydraulic separator comprising in combination a water tank, means for maintaining a predetermined water level therein, a slime separating chamber submerged 95 therein, a supplemental slime separating chamber therefor, in open communication with the primary slime separating chamber below said water level, means for supplying rising current of water in the slime separating chamber, means for conducting sands deposited in the supplemental chamber into the primary slime separating chamber, a revolving means upon which the sands from both chambers are deposited, and an elevating means pivoted to said revolving means 100 adapted to lift and dehydrate said deposited sands and automatically discharge the sands contained therein in a dehydrated condition.

5. A hydraulic separator comprising in combination a primary slime separating chamber open at its bottom for the discharge of the heavier sands therefrom, a supplemental slime separating chamber immediately adjacent thereto, means for producing in said chambers rising currents of water, means for maintaining a predetermined water level in both of said chambers, an opening next below said water level for the passage of slimes containing finer sands settling at the bottom of the supplemental slime separating chamber, and mechanical means for conducting said sands to and discharging them through the bottom of the primary 115 slime separating chamber with the coarser sands.

6. A hydraulic separator comprising in

- combination a primary slime separating chamber provided with a discharge for sand settling therein, a supplemental slime separating chamber immediately adjacent thereto, means for producing rising currents of water in said chambers, means for maintaining a water level common to both of said chambers, an opening between said chambers below said level for the passage of finer sands settling at the bottom of the supplemental chamber, and a screw conveyor adapted for conducting said sands into and from the primary slime separating chamber with the coarser sands.
- 15 7. A hydraulic separator comprising in combination a slime separating chamber, provided with a bottom opening for the discharge of the coarse sands settling therein, a supplemental slime separating chamber immediately adjacent thereto, an open passage laterally through the lower end of the slime separating chamber for the passage of sands therefrom settling in the supplemental chamber, means for maintaining a water level common to both of said chambers above said opening, means for producing ascending currents of water through the slime separating chamber, and a movable device for conducting the sands 25 depositing in the supplemental chamber, into and discharging them with the coarser sands from the slime separating chamber.
- 30 8. A hydraulic separator comprising in combination a primary and a supplemental slime separating chamber, means for adjustably maintaining a water level in and common to both of said chambers, an open passage between said chambers next below said water level, means for producing rising currents of water through the slime separating chambers, a movable means upon which said sands are deposited, means for dehydrating said sands, and means for respectively discharging the dehydrated sands 35 and slimes from the separator.
- 40 9. A hydraulic separator comprising in combination a water tank, a primary slime-separating chamber, a supplemental slime-separating chamber, means for producing rising currents of water in said chambers, and a shifting means for discharging by overflow the coarser sands rising with the slime in the primary chamber.
- 45 10. A hydraulic separator comprising in combination a water tank, a primary slime-separating chamber, a supplemental slime-separating chamber, means for producing

rising currents of water in said chambers, and means in the supplemental chamber for discharging by overflow the slimes and coarser sands rising in the primary chamber.

5 11. A hydraulic separator comprising in combination a water tank, a primary slime-separating chamber, a supplemental slime-separating chamber, and adjustable means at the water level in the supplemental chamber for overflowing and discharging therefrom the slimes and coarser sands rising in and supplied from the primary chamber.

15 12. A hydraulic separator comprising in combination a water tank, a primary slime-separating chamber, a supplemental slime-separating chamber, means for producing agitated rising currents of water in the primary chamber, and a horizontal sliding tray means for discharging by overflow from the supplemental chamber slimes and coarser sands rising in and supplied thereto 20 from the primary chamber.

25 13. A hydraulic separator comprising in combination a water tank, a primary slime-separating chamber, a supplemental slime-separating chamber, means for producing rising currents of water in said chambers, a discharge pipe in the supplemental chamber provided longitudinally with a series of openings, a tray provided transversely with a slot adapted to register with a number of said openings to the exclusion of others, and a series of removable plugs for closing the remainder of said openings.

30 14. A hydraulic separator comprising in combination a water tank, a primary slime-separating chamber, a supplemental slime-separating chamber, means for producing rising currents of water in said chambers, a discharge pipe in the supplemental chamber provided longitudinally with a series of perforations, an adjustable overflow tray provided with a slot adapted to register with a number of said perforations to the exclusion of others for varying the distance of the overflow from the point of entrance 100 of the slimes and sands to the supplemental chamber, and a series of removable plugs for closing the slot in the tray and all other perforations in the pipe.

35 In witness whereof, I have hereunto set my hand and affixed my seal, this 4th day of June A. D. 1919.

HENRY R. WAHL. [L. S.]
